UNITED STATES PATENT OFFICE.

NICOLAS JOSEPH LASCHET, OF DARMSTADT, GERMANY, ASSIGNOR TO THE SIEMENS & HALSKE ELECTRIC COMPANY OF AMERICA, OF CHICAGO, ILLINOIS.

DYNAMO-ELECTRIC MACHINE.

SPECIFICATION forming part of Letters Patent No. 635,489, dated October 24, 1899.

Application filed July 3, 1899. Serial No. 722,754. (No model.)

To all whom it may concern:

Be it known that I, NICOLAS JOSEPH LASCHET, residing at Darmstadt, Empire of Germany, have invented a certain new and useful

5 Improvement in Dynamo-Electric Machines, (Case No. 219,) of which the following is a full, clear, concise, and exact description, reference being had to the accompanying drawings, forming a part of this specification.

10 My invention relates to dynamo-electric machines, and has for its object the provision of improved means for adjusting the air-gap between the armature and fields of such machines. The invention is of particular utility

15 in connection with alternating-current motors of the single-phase or multiphase type, between whose fields and armatures very small air-gaps are very essential. It has heretofore been difficult to effect this adjustment by

20 changing the position of the shafts. By means of my invention the opposed faces of the armature and field may readily be made concentric, so that the air-gap may be of the proper radial width throughout.

25 My invention comprises improved means for adjusting the field or stator portion of the machine. I preferably provide an annular casing and support the field or non-rotatable member within the said casing and provide

30 threaded rods between the said casing and the said member for the purpose of effecting the required adjustment.

35 I will explain my invention more fully by reference to the accompanying drawings, in which—

Figure 1 is a transverse sectional view of a multiphase-current motor employing the adjusting mechanism of my invention. Fig. 2 is a longitudinal sectional view on line 2-2 of

40 Fig. 1.

Like parts are indicated by similar letters of reference in both views.

The rotatable member or rotor *a* has its shaft *b* mounted to rotate in suitable bearings 45 *c c*. These bearings are preferably attached directly to the casing *d*, forming the support for the entire apparatus. The field-core *e* constitutes the core of the field-windings of a multiphase machine. Interposed between the

50 outer periphery of the field-core and the peripheral portion of the surrounding casing are

provided a plurality of adjusting devices *f*, which are preferably in the form of threaded rods extending radially from the shaft *b*, each engaging the outer periphery of the field-core 55 at one end and having threaded engagement at the opposite end with threaded bores provided in enlargements of the casing. To secure the proper axial disposition of the field-core, I preferably form each adjusting device 60 of a number (preferably two) of adjusting- rods *f*, which are interposed between the casing of the field-core, near the radial or end faces of the latter. I have shown three adjusting devices one hundred and twenty degrees apart for effecting the desired adjustment, although the number of adjusting devices may be varied and their relative dispositions may be changed without departing from the spirit of the invention.

70 The operation of the adjusting devices is apparent, since by properly turning the rods *f* of the field-core may be moved in its plane until the desired adjustment of the air-gap between the same and the rotor is secured.

75 Where machines of larger size are to be equipped with the device of my invention, I preferably employ as a further part of each adjusting device a block *g*, these blocks being recessed for engaging the stator to prevent the end thrust thereof, as shown most clearly in Fig. 2, the end portions of the said blocks extending centrally and engaging the radial or end faces of the stator.

80 While I have herein shown and particularly described the preferred embodiment of my invention and a particular application thereof, I do not wish to be limited to the precise construction shown; but,

Having thus described my invention, I 90 claim as new and desire to secure by Letters Patent—

1. In a dynamo-electric machine, the combination with the rotatable and non-rotatable members thereof, of an inclosure for the said members, and adjusting means movable substantially radially interposed between the said inclosure and the non-rotatable member, whereby the accurate adjustment of the air-gap between the said members may be readily effected, substantially as described.

2. In a dynamo-electric machine, the com-

bination with the rotatable and non-rotatable members thereof, of an inclosure for the said members, and a plurality of independently-acting adjusting devices acting substantially 5 radially, distributed around the non-rotatable member and interposed between the inclosure and the non-rotatable member to effect the adjustment of the air-gap between the said members, substantially as described.

10 3. In a dynamo-electric machine, the combination with the rotatable and non-rotatable members thereof, of a casing inclosing the said members, and threaded adjusting devices *ff* distributed around the casing and interposed 15 between the same and the non-rotatable member to effect the adjustment of the air-gap between the said members, substantially as described.

4. In a dynamo-electric machine, the combination with rotatable and non-rotatable members, of a casing inclosing the said members, a plurality of adjusting devices interposed between the said casing and the non-rotatable member for effecting the adjustment of the air-gap, each adjusting device comprising two threaded rods, and a block *g* engaging the inner ends thereof and provided with a recess for engaging the outer periphery of the non-rotatable member to prevent end play thereof, substantially as described. 20 25

In witness whereof I hereunto subscribe my name this 15th day of June, A. D. 1899.

NICOLAS JOSEPH LASCHET.
